ROBERT H. PLASS, OF UPPER MONTCLAIR, NEW JERSEY, ASSIGNOR TO THE CHAPAL-DONNER CORPORATION, OF NEWARK, NEW JERSEY, A CORPORATION OF NEW JERSEY

FUR CUTTING MACHINE

Application filed March 27, 1931. Serial No. 525,668.

This invention relates to improvements in fur cutting machines for cutting animal pelts to remove fur from the skins thereof; such machines being especially useful in the fur hat manufacturing industry.

It is the principal object of this invention to provide a fur cutting machine having a novel construction of means for feeding a pelt to the cutting knives with a step by step movement of small amplitude, whereby the pelt is progressively sheared through close to the roots of the back-turned fur, so that slivers or chips of skin are successively cut away while at the same time severing the fur filaments therefrom with a minimum of waste.

Another object of this invention is to provide a pelt feeding mechanism which is so constructed and arranged as to grip the pelt and feed it forward and then firmly hold the same at points very close to the cutting point of the machine knives while subjected to the shearing action of said cutting knives, whereby the pelt cannot be dragged into the cutting drum so as to produce wasteful cuts, but rather is firmly held against undesired displacement so as to assure only the cutting of narrow slivers to thus assure recovering of fur filaments of maximum length.

Another object of this invention is to provide a pelt feeding mechanism having two sets of cooperative gripping members arranged for alternate feeding operation relative to a pelt, whereby while one set feeds and holds the pelt the other set is retracted to initial feeding position ready for a succeeding feeding and holding operation.

Other objects of this invention, not at this time more particularly enumerated, will be understood from the following detailed description of the same.

An illustrative embodiment of this invention is shown in the accompanying drawings, in which:—

Fig. 1 is a plan view of a fur cutting machine according to the principles of this invention; Fig. 2 is a vertical transverse section, taken on line 2—2 in Fig. 1; Fig. 3 is an enlarged fragmentary vertical transverse section, showing a pelt as operated upon by

the feeding and cutting mechanism of the machine; Fig. 4 is an enlarged fragmentary horizontal section, taken on line 4—4 in Fig. 2; and Fig. 5 is a vertical transverse sectional view, taken on line 5—5 in Fig. 1.

55

Similar characters of reference are employed in all of the hereinabove described views, to indicate corresponding parts.

Referring to said drawings, the reference character 10 indicates the base portion and 11 the end members of a framework, upon which the mechanism of the machine is mounted. Supported in connection with the end members 11 are adjustable bearing members 12. Journaled in and extending between 60 said bearing members 12 is a main shaft 13, upon which is fixed the rotary cutting drum of the machine, comprising a hub-cylinder 14 to which the revolving cutting blades 15 are fixed. Preferably said cutting blades 15 70 are of the helical or curved shape, in longitudinal extension, commonly used in fur cutting machines.

Suitably fixed to and extending between 75 the upper ends of said end members 11, to extend longitudinally across the machine in front of the cutting drum, is a bed-knife support 16. Affixed to said bed-knife support is a bed-knife 17 having its cutting edge 18 downwardly directed to lie tangent to the path of movement of said revolving cutting blades 15 which are carried by said cutting drum. The cutting drum revolves in the direction of the arrow appearing in Fig. 1, whereby the revolving cutting blades 15 are 80 carried upwardly past and in cooperative shearing relation to the cutting edge 18 of said bed-knife 17.

Said cutting drum is enclosed in a hood 19, 90 provided at its forward side with an opening 20 contiguous to said bed-knife 17, whereby by pelts may be fed into operative relation to said bed-knife and the revolving cutting blades cooperating therewith. At the rear of said hood 19 is a discharge mouth 21 95 through which the slivers or chips of skin of the pelt from which the fur has been severed may be discharged to a suitable place of collection.

Suitably supported upon and between the 100

end members 11 is a feed table or plate 22, which is disposed in substantially horizontal plane across the front of the machine, to extend toward the pelt feeding and holding mechanism and cutting point of the machine.

5 The novel pelt feeding and holding means comprises two sets of pelt gripping and advancing devices; each set consisting of pairs of cooperative upper and lower members. 10 The pairs of members of one set of devices being alternated side by side with pairs of members of the other set of devices; means being provided to produce, alternately, the operative feeding strokes of the sets of said devices.

15 Each pair of gripping and advancing members of one set comprises a downwardly directed upper gripper arm 23 and a cooperating upwardly directed lower gripper arm 24; and each pair of gripping and advancing members of the other set comprises a like downwardly directed upper gripper arm 25 and a like cooperating upwardly directed lower gripper arm 26.

20 The upper gripper arms 23 and 25 are all pivotally supported upon a fulcrum shaft 27, which extends across the machine between bearing brackets 28 which are connected with the end members 11 of the machine framework. Said gripper arms 23 and 25 are provided at their lower free ends with inwardly curved and somewhat pointed gripping terminals 29. The gripper arms 23 of one set are provided, intermediate their ends, with 25 outwardly projecting perforate ears 30, whereby the same are pivotally coupled with an oscillator bar or shaft 31; and in like manner the gripper arms 25 of the other set are provided, intermediate their ends, but in another plane, with outwardly projecting perforate ears 32, whereby the same are pivotally coupled with another oscillator bar or shaft 33.

25 Operatively connected with the respective ends of said main drive shaft 13, so as to be actuated thereby, are eccentric members 34, the connecting arms 35 of which are respectively coupled with the respective ends of the oscillator bar or shaft 31; and, in like manner, also operatively connected with the respective ends of said main drive shaft 13, so as to be actuated thereby, are other eccentric members 36, the connecting arms 37 of which are respectively coupled with the respective ends of the oscillator bar or shaft 33.

30 The lower gripper arms 24 are carried by and at the free ends of lever members 38, which are arranged substantially at right angles to said gripper arms, and which, at their opposite ends, are provided with slotted ears 39 to receive a fulcrum shaft 40, thus so mounting the same that they are capable both of swinging oscillation on said fulcrum shaft 40 and also of longitudinal reciprocation. Connected with the fulcrumed ends of

35 said lever members 38 are upstanding lugs 41 to which are connected anchor pull springs 42. The means for actuating said lever members 38 and the gripper arms 24 carried thereby comprises a cam shaft 43 which extends 40 across and above the free ends of the lever members 38 within the angle formed therewith by said gripper arms 24. Said cam shaft is provided with eccentric cam members 44 which correspond to and operatively engage said lever members 38 and their gripper arms 24, which are tensionally held to such engagement by said pull springs 42.

45 The lower gripper arms 26 are also carried by lever members 45, similarly mounted on said fulcrum shafts 40 for oscillation and reciprocation and similarly tensioned by pull springs 42 in operative relation to the cam members 46 of a second cam shaft 47.

50 Said cam shaft 43 is driven from the main shaft 13 by a sprocket and chain drive 48, and said second cam shaft 47 is driven from cam shaft 43 by interconnecting gearing 49. It will be obvious, however, that any other suitable forms of transmission means may be 55 employed for driving said cam shafts.

55 Preferably said lever members 38 and 45 and their actuating cam shafts 43 and 47 are suitably enclosed in a casing 50 adapted to contain oil or other suitable lubricant in 60 which these parts are bathed.

65 Extending along and in front of the cutting point of the machine, intermediate the same and the inner end of the feed table 22, is any suitable means for discharging the 70 severed fur yielded by the cutting operations. Illustrative of one such means, I have shown the same to consist of a suction box 51 having its perforate top adjacent to and somewhat below the cutting point of the machine; said suction box being connected by a conduit 52 to any suitable form of air 75 suction pump (not shown). Running over the suction box 51, so as to traverse its perforate top, is an endless conveyor belt 53 of air pervious material. Below said suction box is a belt driving roller 54, the shaft 55 of which is journaled in the end members 11 of the machine framework. Suitable means are provided for actuating said roller 54.

80 For example, rotatable on a stud shaft 56 is a gear 57 which is driven from the gearing 49 of the cam shafts, to in turn actuate a sprocket and chain drive 58 for driving the shaft 55 and roller 54. Angularly directed 85 against the fur discharging course of said conveyor belt 53 is an inclined chute plate 59 by which severed fur is removed from the discharging course of said conveyor belt 53, to be thence delivered out of the machine.

90 In the operation of the machine, the pelt, fur side down, is pushed by the operator over the feed table 22 toward the gripping and advancing members by which it is engaged and advanced to the cutting point of the 95

machine. By virtue of the operation of the actuating means controlling their movements, one set of said members, comprising co-operative pairs of gripper arms, being first swung outward and separated so that the pelt may pass therebetween, are brought together in gripping relation to the pelt, and then moved inwardly toward the cutting point of the machine, thus carrying the forward edge of the pelt so that the same is projected slightly over the edge of the bed-knife 17, over which it is held by said gripper arms to lie in the path of the revolving cutting blades 15. The forward movement of the pelt over the feed table 22 tends to lay back the fur, and consequently when a revolving cutting blade 15 shears off the edge of the pelt skin projected over the bed-knife 15, a sliver or chip of the skin is cut or sheared off, at the same time severing the fur therefrom close to the roots thereof. The fur thus severed is drawn by the suction produced at the perforate top of the suction box 51 down upon the conveyer belt 53, to thereby be carried to the chute plate 59 over which it moves to a place of collection. These operations are continued by alternative feeding operations of the respective sets of pelt advancing and gripping members.

The timed operation of the sets of pelt advancing and gripping means is as follows:—
By operation of the eccentrics 34, the oscillator bar 31 is thrust outward, to thereby swing the upper gripper arms 23 outward; at the same time the cams 44 of cam shaft 43 are timed to push outward the lever members 38 and the gripper arms 24, while at the same time depressing the same, whereby the extremities of the latter are separated from the extremities of the gripper arms 23, thereby releasing the grip of these parts upon the pelt while they are retracted for repetition of a pelt feeding stroke. The reverse strokes of the eccentrics 34 now swing downward and inward the gripper arms 23, while the cams 44 moving away from the lever members 38 thereby permit the latter, under pull of their springs 42 to first swing upward to carry the lower gripper arms 24 into opposed gripping relation to the gripper arms 23, and thereupon as the cams 44 continue to move away from the bases of said gripper arms 24, allow the latter to travel inward in company with the inwardly swinging gripper arms 23, thus carrying the gripped pelt forward to advance the same over the bed-knife. The gripping arms 23—24 continue to hold the pelt, while the sliver or chip of skin is cut therefrom with fur severing effect. In the meantime by similar action of the controlling eccentrics 36 and cams 46, the gripper arms 25—26 are separated and swing out or are retracted to initiate another pelt feeding and holding stroke, which is timed to take place as soon as the gripper arms

23—24 release the pelt upon completion of a shearing stroke of the cutting mechanism. It will thus be obvious that the two sets of pelt feeding and holding devices will operate alternatively to produce a step by step feeding advance of the pelt until it is entirely consumed and the hair thereby severed therefrom.

From the above description it will be understood that not only is the pelt under control at all times during its movement to the cutting mechanism of the machine, but that by reason of the peculiar design of the oscillatable gripper arms, the pelt may be gripped and held extremely close to the cutting point of the machine. This is of particular advantage, since it assures means for holding and controlling the extreme rear or trailing end of the pelt against being dragged into the machine before being properly consumed with fur severing effect, and consequently waste of fur with uncut tailings of pelts is eliminated.

I am aware that many changes could be made in the above described mechanisms as well as in the details of the construction thereof, without departing from the scope of this invention as defined in the appended claims; it is therefore intended that all matter contained in the above description or shown in the accompanying drawings shall be interpreted as illustrative and not in a limiting sense.

I claim:—

1. In a fur cutting machine, a cutting mechanism, and means to feed a pelt to said cutting mechanism, said feeding means comprising opposed gripping devices to engage opposite sides of a pelt, and means to oscillate said gripping devices toward and from said cutting mechanism to move said pelt step by step toward the latter.

2. In a fur cutting machine, a cutting mechanism, sets of opposed oscillatable gripping devices to engage opposite sides of a pelt to advance the same step by step to the cutting mechanism, and means arranged to actuate said sets of gripping devices with alternate pelt gripping and advancing effect.

3. In a fur cutting machine, a cutting mechanism, and means to feed a pelt to said cutting mechanism, said feeding means including upper and lower gripping arms in opposed relation and mounted for movement toward and from each other to intermittently grip a pelt therebetween and also for movement toward the cutting mechanism when engaged with a pelt but away from the cutting mechanism when in released relation to said pelt.

4. In a fur cutting machine, a cutting mechanism, and means to feed a pelt to said cutting mechanism, said feeding means including upper and lower gripping arms in opposed relation and mounted for movement toward and from each other to intermittent-

ly grip a pelt therebetween and also for movement toward the cutting mechanism when engaged with a pelt but away from the cutting mechanism when in released relation to said pelt, and said gripping arms being further arranged in alternately operative sets.

5. In a fur cutting machine, a cutting mechanism, and means to feed a pelt to said cutting mechanism, said feeding means including upper and lower gripping arms in opposed relation and mounted for movement toward and from each other to intermittently grip a pelt therebetween and also for movement toward the cutting mechanism when engaged with a pelt but away from the cutting mechanism when in released relation to said pelt, means for actuating said upper gripping arms, and means for simultaneously actuating said lower gripper arms.

6. In a fur cutting machine, a cutting mechanism, and means to feed a pelt to said cutting mechanism, said feeding means including upper and lower gripping arms in opposed relation and mounted for movement toward and from each other to intermittently grip a pelt therebetween and also for movement toward the cutting mechanism when engaged with a pelt but away from the cutting mechanism when in released relation to said pelt, means for actuating said upper gripping arms, and means for simultaneously actuating said lower gripper arms, a pelt supporting table extending toward said feeding means, and a severed fur receiving and discharging means adjacent to said cutting mechanism and feeding means.

7. In a fur cutting machine, a cutting mechanism, and means to feed a pelt to said cutting mechanism, said feeding means comprising upper gripping arms pivoted to oscillate toward and from said cutting mechanism, lower gripping arms arranged to cooperatively oppose said upper gripping arms and mounted for compound oscillation toward and from said cutting mechanism and toward and from said upper gripping arms, said upper and lower gripping arms cooperating to engage a pelt to advance the same step by step to said cutting mechanism and to hold said pelt against displacement while subject to cutting effect of the latter mechanism, actuating means for oscillating said upper gripping arms, and actuating means for simultaneously oscillating said lower gripping arms cooperatively with said upper gripping arms.

8. In a fur cutting machine, a cutting mechanism, and means to feed a pelt to said cutting mechanism, said feeding means comprising upper gripping arms pivoted to oscillate toward and from said cutting mechanism, lower gripping arms arranged to cooperatively oppose said upper gripping arms

and mounted for compound oscillation toward and from said cutting mechanism and toward and from said upper gripping arms, said upper and lower gripping arms cooperating to engage a pelt to advance the same step by step to said cutting mechanism and to hold said pelt against displacement while subject to cutting effect of the latter mechanism, actuating means for oscillating said upper gripping arms, and actuating means for simultaneously oscillating said lower gripping arms cooperatively with said upper gripping arms, and said cooperative upper and lower gripping arms and their actuating means being arranged in alternately operating sets.

9. In a fur cutting machine, a cutting mechanism, and means to feed a pelt to said cutting mechanism, said feeding means comprising upper gripping arms pivoted to oscillate toward and from said cutting mechanism, lower gripping arms arranged to cooperatively oppose said upper gripping arms and mounted for compound oscillation toward and from said cutting mechanism and toward and from said upper gripping arms, said upper and lower gripping arms cooperating to engage a pelt to advance the same step by step to said cutting mechanism and to hold said pelt against displacement while subject to cutting effect of the latter mechanism, actuating means for oscillating said upper gripping arms, and actuating means for simultaneously oscillating said lower gripping arms cooperatively with said upper gripping arms, a pelt supporting table extending toward said feeding means, and a severed fur receiving and discharging means adjacent to said cutting mechanism and feeding means.

10. In a fur cutting machine as defined in claim 7, in which said actuating means for said upper gripping arms comprises an oscillator bar with which the same are connected, and eccentric drivers for oscillating said bar.

11. In a fur cutting machine as defined in claim 7, in which said actuating means for said lower gripping arms comprises spring tensioned lower members to carry the same, said lever members being mounted for both up and down pivotal movement as well as longitudinal reciprocatory movement, and rotatable cam means for effecting such compound movement.

12. In a fur cutting machine as defined in claim 7, in which said actuating means for said upper gripping arms comprises an oscillator bar with which the same are connected, and eccentric drivers for oscillating said bar, and in which said actuating means for said lower gripping arms comprises spring tensioned lever members to carry the same, said lever members being mounted for both up and down pivotal movement as well as bodily longitudinal reciprocatory movement, and rotatable cam means for effecting such com-

pound movement in cooperative timed relation to the oscillatory movement of said upper gripping arms.

In testimony, that I claim the invention set forth above I have hereunto set my hand this 24th day of March, 1931.
